AWNING

James E. Jones, Toledo, Ohio, assignor to The Hettrick Manufacturing Company, Toledo, Ohio, a corporation of Ohio

Application December 13, 1954, Serial No. 33,489

Term of patent 14 years

(Cl. D21—6)

Figure 1 is a front perspective view of the awning in its position of use, showing my new design, the opposite side not shown having substantially the same appearance; and

Figure 2 is a front perspective view of the awning shown in Figure 1, only in its raised position.

The broken line showing of a window in the drawing figures is for illustrative purposes only.

I claim:

The ornamental design for an awning, as shown and described.
